(57) **CLAIM**

The ornamental design for a integral pivoting faucet, as shown and described.

DESCRIPTION

FIG. 1 is a perspective view of an integral pivoting faucet, showing my new design;

FIG. 2 is a front elevational view thereof;

FIG. 3 is a rear elevational view thereof;

FIG. 4 is a top plan view thereof;

FIG. 5 is a bottom view thereof;

FIG. 6 is a right side elevational view thereof;

FIG. 7 is a perspective view thereof; shown in a partially extended position of use; and,

FIG. 8 is a perspective view of my design, shown in a fully extended position of use.

The portions in dotted lines are shown for environmental purposes only, and form no part of the claimed design.
